ATTORNEY

UNITED STATES PATENT OFFICE

KURT WIEGAND, OF BERLIN, GERMANY, ASSIGNOR TO GENERAL ELECTRIC COMPANY,
A CORPORATION OF NEW YORK

ELECTRIC LIGHTING TUBE

Application filed October 21, 1927, Serial No. 227,798, and in Germany January 19, 1927.

The present invention relates to electric lighting tubes of the kind wherein the electrode container is enclosed in a casing.

In my copending application, Serial No. 226,994, filed October 18, 1927, there is described an electric glow tube, the electrode containers of which are enclosed in a metal casing connected to earth for the purpose of reducing the perforation voltage and having a small space requirement, with the interposition of a non-hydroscopic insulation, advantageously with the interposition of glass bodies. In accordance with the present invention the same purpose is obtained, however, with the omission of a specially made and to be attached metal casing, by the use of an insulating body, say of porcelain, enclosing the electrode container and which on the outside has a tightly adhering metal coating. The metal coating is obtained in any desired manner, for example by the squirting on of liquid metal or in a galvanic way, and gives in the same manner as the former metal casing, the possibility of applying an earth connection to the electrode container.

In order to easily attach the box-like insulating body to the electrode container and to be able to also easily inspect the latter, the exteriorly conductively formed insulating body consists advantageously of two cups of approximately semi-cylindrical shape engaging with each other and clamped by means of projecting noses. The screws serving for the clamping fast of the two cups of the insulating body can at the same time be used for the connecting up of the earth connection.

In the drawing is shown an example of construction of an enclosed electrode container of my invention, in longitudinal section in Figure 1 and in cross section in Figure 2.

In the forms of construction shown in the main patent the electrode container *b* attached to the end of the glow tube *a* has in the interior a sheet metal electrode *c*, which is connected to the cable *d*. The electrode container is in this case enclosed by a casing-like insulating body, say of porcelain, which is closed off at one end by the metal cap *f* set onto the cable *d* and at the other end by a

rubber cap *g* put onto the glow tube *a*. The casing-like insulating body consists of two approximately half-cylindrical cups *n*¹, *n*² placed together and having interlocking parts comprising the nose-like projections *o* attached to cup *n*¹, which engage in corresponding recesses on cup *n*² and the lugs *p* attached to cup *n*² which engage the cup *n*¹ from the outside. Both cups *n*¹, *n*² are further tightly clamped to each other by the screws *q*. The entire outside surfaces of both cup parts *n*¹, *n*² of the casing-like insulating body are provided with a tightly adhering metal coating *r*, which is connected to earth in a suitable manner and advantageously by means of the clamping screw *q*.

What I claim as new and desire to secure by Letters Patent of the United States, is,—

1. An electric discharge device having an electrode container, an insulating sheath around said container, and a metallic coating on the exterior surface of said sheath. 70

2. An electric discharge device having an electrode container, an insulating sheath around said container, said sheath being 75 formed of a plurality of separable components, and a metallic coating on the exterior surface of said sheath.

3. An electric discharge device having an electrode container, an insulating sheath 80 around said container, said sheath consisting of two similar sections, and a metallic coating on the exterior surface of said sheath.

4. An electric discharge device having an electrode container, an insulating sheath 85 around said container, said sheath being formed of a plurality of separable components, means on said components for holding said components together to form said sheath, and a metallic coating on the exterior 90 surface of said sheath.

In witness whereof, I have hereunto set my hand this 6th day of October, 1927.

KURT WIEGAND.
